CARL J. ANDERSON, OF BROOKLYN, NEW YORK

ADJUSTABLE SHADE ROLLER SUPPORT

Application filed February 9, 1932. Serial No. 591,910.

This invention relates generally to the class of supports, and has particular reference to a window shade roller bracket or support.

5 The invention broadly comprehends a support for window shade rollers which is so constructed and arranged as to readily permit of the shifting or vertical adjustment of the roller whereby the shade may be unrolled or drawn to optionally cover or shade the 10 complete area of the window or various portions of said area.

More particularly, the invention resides in an improved means for mounting on a window frame, the brackets for supporting a shade roller whereby said brackets may be simultaneously adjusted vertically and effectually detained in the adjusted position.

15 The invention further contemplates a device of the indicated character which is so constructed as to permit of its substitution for the usual fixed supports whereby it will accommodate without alteration shades and shade rollers which have been previously 20 installed.

Other objects of the invention reside in the comparative simplicity of construction of the device, the economy with which it may be produced and installed and the general 25 efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a fragmentary front view of a window equipped with a shade roller mounting or support constructed in accordance 40 with the invention.

Figure 2 is a fragmentary enlarged vertical sectional view taken approximately on the line indicated at 2-2 in Figure 1.

45 Figure 3 is a similar view taken approximately on the line indicated at 3-3 in Figure 4.

Figure 4 is a fragmentary sectional view taken approximately on the line 4-4 of Figure 2.

Figure 5 is a horizontal sectional view taken approximately on the line 5-5 of Figure 4.

Figure 6 is an enlarged detail view of one end of the pinion coupling rod, with parts broken away and shown in section to disclose the underlying structure.

Figure 7 is a detail front view of a modified form of the detent means, parts being shown in section.

Figure 8 is a sectional view taken approximately on the line 8-8 of Figure 7.

Referring to the drawings by characters of reference, A and B designate respectively the opposite sides of a window frame, in which the usual upper and lower sashes C and D are slidable.

The window shade roller support constituting the present invention includes a pair of guides 10 and 11 which are secured to the inner confronting side faces of the frame sides A and B and which extend from the upper member E of the window frame downwardly an appropriate distance, depending upon the range of vertical adjustment of the shade roller which is desired.

The guides 10 and 11 are in the nature of channeled strips defining a groove 12 of dovetail cross sectional configuration and having depressed or offset portions 13 spaced longitudinally thereof to accommodate there-

through screws or other fastening devices 14 which are anchored in the sides A and B of the window frame structure. This disposes the screw heads within the confines of the depressed portions and below the surface of the groove so as not to interfere with the movement of the elements to be guided in the guides 10.

The outermost sides of the guides 10 and 11 or the sides which are disposed adjacent the sashes C and D are provided with a flange 15 extending in a plane parallel to the base of the guide strip and formed with a right angular terminal 16 which extends outwardly from and is disposed in a plane perpendicular to the plane of the base of the strip.

The terminal 16 is formed with a longitudinal series of perforations or apertures 17 which define rack teeth for a purpose to be hereinafter set forth. A bracket carrier 18 is arranged to slide longitudinally

of each guide strip and the base portion 19 thereof is of a cross sectional configuration to fit within the dovetail groove 12, whereby said carrier is retained against lateral or transverse displacement and limited to sliding movement in the guide. Each carrier 18 is of such thickness as to dispose its outer face 20 in a plane slightly beyond the free end of the terminal 16, and said carrier 18 is provided with a recess 21 opening through the face 20 and extending inwardly to a depth in a plane coinciding approximately with the plane of the flange 15. A pinion 22 is mounted within the recess 21 and is formed with a journal or trunnion 23 which is received and bears in a bearing opening 24 in the body of the carrier 18. The pinion is further provided with an outwardly projecting tubular stub shaft 25 which is formed with longitudinal diametrically opposed slots 26 opening through its outer end. A combined cover plate and bracket body 27 is secured to the face 20 by screws or equivalent fastening devices 28, and the same is formed with a bearing opening through which the stub shaft 25 protrudes and within which the same bears. The diameter of the pinion 22 is such as to dispose its peripheral teeth 30 in a position to mesh with the rack teeth formed by the perforations or apertures 17 in the terminal 16, so that longitudinal sliding movement of the bracket carrier imparts rotation to the pinion 22. The cover plate and bracket body is provided with a rearwardly or outwardly directed extension 31 having a laterally inwardly directed lip 32 which engages behind the free end of the terminal 16 and further assists in the longitudinal guiding of the bracket carrier in the guide strips 10 and 11. Each cover plate and bracket body 27 is formed with a forwardly projecting bracket portion 33 provided with a bearing slot or opening 34 to accommodate the respective rotary and non-rotary trunnions of a spring shade roller. It will be observed particularly in Figure 5 that the bracket 33 is offset laterally so as to accommodate a shade roller of maximum length and a shade of maximum width.

In order to insure the movement of the bracket carriers and brackets in unison so as to avoid possible canting of the shade and shade roller, a connecting rod or shaft 35 is provided, the opposite ends of which are secured to the stub shafts 25 for rotation therewith. As particularly illustrated in Figure 6, the rod or shaft 35 is of tubular formation and is provided at its opposite ends with terminal pieces 36, a portion 37 of which is telescopically received within the end of the shaft or tube 35 and grooved as at 38 to receive the inwardly pressed portion 39. This locks the terminal pieces within the ends of the shaft or rod 35. The free extremity 40 of the protruding portion of each terminal piece

36 is enlarged and longitudinally arcuated to provide a friction head to be frictionally engaged within the slotted end of the stub shaft 25. The head 40 is provided with a transverse pin or key 41 which protrudes beyond diametrically opposite sides of the head to engage within the slots 26 of the stub shaft 25. This arrangement couples the pinions for turning movement in unison and insures simultaneous sliding of the bracket carriers 18 and brackets. 75

In order to provide means for facilitating the vertical adjustment of the brackets and bracket carriers, one of the bracket carriers has secured thereto and depending therefrom a stem 42, by virtue of which movement of the brackets and bracket carriers and vertical adjustment of the shade and shade roller may be effected without the necessity of reaching upwardly. 80

In order to provide means for detaining or retaining the brackets and bracket carriers in vertically adjusted position, a detent 43 is provided which is normally urged by a spring 44 into engagement with two adjacent teeth of one of the pinions, in the present instance that shown at the left side of the window in Figure 1. As illustrated in Figures 3 and 4, the detent 43 is in the nature of a flat blade which is slidably guided in a vertical slot 45 formed in the carrier body 18 and opening through the outer face 20 thereof. In this instance, the detent blade is formed with a circular depending shank 46 and the stem 42 is hollow to receive the shank 46 and extends into a bore 47 in the lower end of the carrier body 18, where it is suitably retained in place frictionally or otherwise. The shank 46 is provided with a depending rod 48 which extends downwardly through the hollow stem 42 and protrudes beyond the cap or head 49 at the lower end of the stem. The protruding portion of the rod 48 is provided with a manipulating button 50. At the juncture of the shank 46 with the rod 48, a shoulder 51 is formed and the stem is provided with an internal seat 52. The detent spring 44 surrounds the rod 48 and is interposed between the shoulder 51 and the seat 52. 95

In use and operation, the shade roller indicated in broken lines at F is mounted in the usual manner in the brackets 33. The vertical adjustment of the brackets and bracket carriers is accomplished by first exerting a downward pull on the manipulating button 50 to retract the detent blade 43, thereby releasing the pinion 22. By retaining the manipulating button in this position, an upward push or downward pull on the stem 42 will effect vertical movement of the bracket carrier, brackets and shade roller and shade. When the desired vertical adjustment is obtained, the button 50 is released and the detent spring 44 will reengage the detent to 100

110

detain or retain the devices in adjusted position.

In the modified form of adjusting stem and detent means illustrated in Figures 7 and 8, the detent blade 43a extends downwardly through the stem 42a and is provided adjacent its lower end with a circular shank 46a which defines at its juncture with the blade, a shoulder 51a. The cap or head 49a at the lower end of the stem 42a in this instance houses the detent spring 44a which bears against the outer end 45a of the cap or head. In other respects, the stem and detent means are identical with that described in the preferred form of the invention.

What is claimed is:

1. A support for window shade rollers including a pair of vertically disposed guides 20 secured to a window frame at opposite sides thereof and each having a set of rack teeth, a bracket slidable in each guide, a pinion journaled on each bracket and engaging the rack teeth, a shaft keyed at its opposite ends 25 to said pinions and connecting the same for movement in unison, detent means for locking the pinion of one of the brackets to retain both brackets in vertically adjusted position, a bracket moving element secured to 30 one of the brackets and depending therefrom and detent releasing means extending through said element.

2. In a device of the class described, a pair of cross sectionally dovetailed guide strips, 35 each having a perforated flange at one of its edges defining a rack, a carrier having a dovetailed base slidable in each guide strip and having a recessed outer face, a pinion engaging the rack, located in the recessed face 40 of the carrier and having a shaft bearing in the carrier and a cover plate secured to the outer face of the carrier to retain the pinion in the recess, said cover plate being formed with a forward projection fashioned to form 45 a shade roller bracket.

3. In a device of the class described, a pair of cross sectionally dovetailed guide strips, each having a perforated flange at one of its 50 edges defining a rack, a carrier having a dovetailed base slidable in each guide strip and having a recessed outer face, a pinion engaging the rack, located in the recessed face of the carrier and having a shaft bearing in the carrier and a cover plate secured to the outer face of the carrier to retain the pinion in the recess, said cover plate being formed 55 with a forward projection fashioned to form a shade roller bracket and said pinion having a tubular stub shaft protruding through the cover plate and formed with an inwardly extending slot for removably receiving the key pin on the end of a connecting rod.

4. In a device of the class described, a pair of cross sectionally dovetailed guide strips, 60 each having a perforated flange at one of

its edges defining a rack, a carrier having a dovetailed base slidable in each guide strip and having a recessed outer face, a pinion engaging the rack, located in the recessed face of the carrier and having a shaft bearing in the carrier and a cover plate secured to the outer face of the carrier to retain the pinion in the recess, said cover plate being formed with a forward projection fashioned to form a shade roller bracket and having a rearward projection engaging around the rack defining flange.

5. A support for window shade roller brackets including a pair of vertically disposed guides secured in confronting relation 80 to the opposite sides of a window frame, a bracket carrier slidable in each guide, a rack on each guide, a pinion journaled in each carrier engaging with said racks, an element 85 detachably connected with each pinion for causing the same to move in unison, said element being held in connected relation with the pinions by the engagement of the carriers in the guides and releasable from the pinions by the removal of the carriers from the guides. 90
